MAX WOLNIK, OF BROOKLYN, NEW YORK

MECHANISM FOR RECEIVING AND WEIGHING COINS

Application filed July 19, 1929. Serial No. 379,365.

This invention relates to coin-controlled vending machines and particularly, to the means for insuring the operation of the vending mechanism only by a predetermined number of coins of the proper denomination.

In my co-pending application for patent for coin-controlled automatic liquid vending machine, filed May 22nd, 1928, Serial No. 279,645, I have shown coin-controlled mechanism dependent upon the insertion of a proper number of coins of the proper denomination for operating the vending devices. This invention is an improvement on the mechanism shown in said co-pending application and is designed particularly, to depend for its proper operation upon the weight of the coins, as well as the size and number thereof, so that operation of the machine by counterfeit coins or slugs of improper weight or size becomes impossible.

The various objects of my invention will be clear from the description which follows and from the drawings, in which,

Fig. 1 is a perspective view of my improved mechanism, showing the normal or initial positions of the parts.

Fig. 2 is a vertical section and side view of the same, and

Fig. 3 is a perspective view similar to Fig. 1, showing the positions assumed by the parts after the mechanism has been operated to actuate the vending devices, and before the parts have been returned to the initial positions thereof.

In that practical embodiment of my invention which I have illustrated by way of example, as applied to any vending machine such as for example, a machine for vending liquids, a suitable valve or other member of a vending mechanism as 10 is supported by means of a bearing as 11 secured to the casing 12. Said vending member 10 is preferably provided with a suitable projection as 13 arranged to be operated directly by the exposed portion of the face of the uppermost or other coin held in the coin receptacle or chute 14, in a manner which has been described in my co-pending application above-mentioned. The coin chute or receptacle 14 is designed to receive a predeter-

mined number of coins of predetermined denomination, size and weight, so that on the swinging of the chute, the vending member 13 is actuated to deliver the material sold by the machine. For that purpose, the upper portion of the chute may be slotted as at 15, to expose the uppermost coin 16, or other part of the substantially vertical row of coins whereby rearward movement of the chute together with said row causes the coin to contact with the projection 13 and to operate the member 10, provided that the said uppermost coin 16 is properly arranged in the chute 14. A supporting band as 19 is passed about said chute and is suitably secured to the shaft 17, which is in turn pivotally mounted in a suitable bracket 18 secured to the casing 12.

At one end of the shaft 17 and outside of the casing 12 is an operating crank as 20, secured to said shaft and by means of which said shaft may be rotated in either direction for the purpose of swinging the coin chute in the proper direction when desired.

At the lower end of the chute 14, a slot as 21 is made, into which is partly inserted the coin supporting member 22. Said member is preferably made wider at the rear end 23 thereof than at the front end 24, and is secured to the rod or lever member 25. Said member 25 together with the coin support 22 are movable vertically relatively to the slot 21, the lever, of which the rod 25 forms a part, being pivoted to the bar 26 as by means of the ring 27, whereby the rod 25 and the parts carried thereby at the right of the lever as viewed in Fig. 1 may also move forwardly and rearwardly about the pivot point.

The bar 26 is in turn pivoted at its rear end to be casing 12 as at 28, a suitable stop as 29 being provided to limit the downward movement of the forward end thereof. The lever of which said bar 26 is a part, is preferably made in two parts, one part as 30 being hollow for the reception of the other part consisting of the rod 25 and said parts being normally held together by means of a suitable coil spring 31, whereby the solid rod portion 25 of the lever is yieldably con-

nected to the hollow portion 30 while the parts may rotate relatively to each other.

At the left end of said hollow portion is secured the weight container 32 adapted to receive weights for the purpose of normally maintaining the rod 25 in predetermined position, wherein the member 22 may be partly inserted into the slot 21. The right end of the rod 25 terminates in a wedge 33 adapted to be gripped by certain of the teeth 34 of the rack 35, which is secured to the shaft 17, so that said wedge and there-through the rod 25 may be moved as will be hereinafter described.

The weight container 32 is connected to the projection 13 preferably by means of a suitable flexible element, such as a string 36 passing over the pulley 37 and secured at one end thereof to the rod 38 extending from the projection 13, and at the other end to the ear 39 of the weight container 32. The string 36 is normally slack but is made preferably of just sufficient length to accomplish the ends and to operate as desired. If desired, a suitable spring may be interposed between the ends of the flexible element 36, said spring in that case being of insufficient strength to affect any movement of the projection 13, except as tension is put on the spring.

It will be understood that in the normal positions of the parts after the coins have been inserted into the coin chutes, and as shown in Fig. 1, the string 36 is sufficiently slack to allow the slackness to be taken out and the string tensioned when the crank 20 is rotated in the proper direction. At this time, the lever rod 25 has been depressed by the weight of the coins in the chute such an amount that the member 22 has been partly or entirely removed from the slot 21.

The member 50 pivoted to the support 52 as at 51 is pulled by the spring 53 rearwardly so that its edge 54 contacts with the flat front edge 55 of the wedge 33 and maintains said wedge against rotation, at the same time pushing the rod 25 against a suitable stop as 56 and thereby preventing rearward bodily movement of said rod under the influence of the spring 53. The member 50 also serves to restore the wedge 33 to its original position after it has been moved therefrom, and tends to urge the wedge into engagement with the teeth 34 of the rack 35; a suitable spring as 65 connected at one end to the chute 14 below the band 19 and at its other end, to the rear of the casing 12, serves to urge the chute toward its initial position wherein the upper end of said chute is directly underneath the stationary chute 60 secured to the top 66 of the casing (Figs. 2 and 3).

The operation of my improved machine is as follows:

Coins are dropped by the user into the

chute 60 in the usual manner as from the outside of the casing 12. The coins pass through the chute 60 and into the chute 14. As the coins drop to the bottom of the chute 14, they rest on the upper edge of the coin support 22 and are arranged in a vertical row within said chute. It will be understood that the weight of each coin depresses the lever rod 25 to a slight extent against the action of the weights in the container 32.

After the predetermined number of coins of predetermined denomination have been inserted into the chute, the weight of said coins depresses the rod 25 to a certain predetermined extent, said rod swinging downwardly about its pivot 27 until the wedge 33 is brought opposite certain predetermined teeth of the rack 35, the amount of depression of the rod 25 having been carefully predetermined so that the uppermost coin of the row becomes exposed in the slot 16 ready to operate the vending mechanism on the swinging of the chute.

It will be understood that coins or slugs which are too heavy will depress the rod 25 more than the predetermined amount, and that therefore, no coins will be exposed in the slot 16 in position to operate the projection 13, and that if the coins are much too heavy, the rod will be depressed to such an extent that the coins will drop out of the chute 14 into the coin receptacle 41. If, on the other hand, the coins are too light in weight, the rod 25 will be depressed by the weight of the coins to an insufficient extent to allow the uppermost coin to be properly positioned in the slot 16 so that said coin will project out of said slot and will remain partly in the chute 60 and partly in the chute 14, to prevent relative movement of said chutes, and hence preventing operation of the vending mechanism through the projection 13.

The balanced lever rod 25 now having been depressed, and the wedge 33 brought into position for engagement by the rack teeth 34, the crank 20 may be swung rearwardly, whereby the shaft 17 is rotated and the bottom of the chute 14 carried a slight distance over the member 22 toward the end 115 24 thereof. At the same time, the rack 35 is brought forwardly, the teeth 34 firmly clamping the wedge 33 soon after the beginning of the stroke, and thereby prevents movement of the lever rod 25 relatively to the rack 35, so that the parts are locked together and move as a unit after the rack and wedge are clamped.

Toward the end of the stroke, movement of the crank 20 rotates the rod 25 about its axis, the edge of said wedge moving downwardly against the action of the spring 31 and the container 32 and its ear 39 moving slightly rearwardly, being allowed to do so by reason of the loose fit of the ring 27 on the bar 26,

while the wedge 33 also moves bodily upwardly. Being locked by the ring 27 to the bar 26 in this direction, upward movement of the wedge causes upward movement of the rod 25, the lever section 30, and of the bar 26 as shown in Fig. 3. The slack in the string 36 is not thereby substantially affected.

As the lower end of the chute moves forwardly, the upper end moves rearwardly and the coin exposed therein strikes the projection 13 and rotates the operating member to perform the vending operation. Rearward movement of said projection, however, tensions the string 36, taking up the slack there-
10 in produced by the rearward movement of the ear 39, and the original slack in the string, and exerting an upward pull upon the container 32. Said container and the rod 25 connected thereto, however, are not per-
15 mitted to move further, due to the locking of the wedge 33 by the teeth 34. When the crank 20 is released, however, the spring 55 pulls the lower end of the chute 14 rearwardly and returns the crank 20, the shaft 17, the rack 35 and the wedge 33 (urged by the member 50) to their initial positions as indicated in Fig. 1. On the last part of the return movement, the rack 35 and the teeth 34 thereof suddenly release the wedge, and
20 due to the sudden release, and to the upward pull upon the container 32 by reason of the force exerted thereon by the tension of the string 36, the container 32 moves upwardly while the rod 25 drops downwardly. The
25 member 22 therefore at this time moves downwardly a sufficient distance to allow the coins to drop out of the chute 14 and into the receptacle 41.

This discharge operation may be aided if desired, by the interposition of a spring between the ends of the string 36, though I have not found such a spring to be necessary, the lever rod 25 dropping to give the coins ample time to drop out of the chute 14 by
45 gravity, so long as the projection 13 remains in its rearmost position.

After the vending mechanism has been operated by the projection 13, said projection may be returned to its original position manually or automatically, in a manner which need not be shown or described and which is clearly set forth in my said copending application. The string 36 is thereby slackened and the container 32 released from its upward pull. Said container is thereby freed and drops, raising the wedge 33 and the coin support 22 to their initial positions ready for the repetition of the operation.

Should the user desire to have his coins returned before he has completed the operation and before all of the coins have been inserted into the machine, he need merely turn the crank 20 forwardly whereby the lower end of the chute 14 is moved rearwardly past the rear end of the coin support

22 so that the coins are free to drop down the return chute 61.

In order to insure the rotation of the rod 25 and the proper lifting of the lever including the member 30, the container 32 and the bar 26 on the rearward rotation of the crank 20, as has been hereinbefore fully described, an additional connection may be made between the shaft 17 and the hollow member 30 to supplement the action of the rack 35 and the wedge 33. This additional member may take the form of a suitable wire or other member shaped like a crank and secured at one end to the shaft 17 and having one leg thereof of sufficient length to pass underneath and to contact with the member 30.

Such an additional member serves the purpose of exerting lifting force upon the weighing lever at the end opposite to that upon which similar force is exerted through the rack and wedge.

As has been hereinbefore explained, coins which are too light in weight remain partly in the chute 60 and prevent operation of the machine.

In order to allow the removal of such coins or slugs, I prefer to hinge the lower part 62 of the sides of the chute 60 to the remainder of the sides, as by means of a suitable spring hinge 63 of any well known type. Said hinge serves to keep the parts 62 in their normal or operative positions but allows the swinging of said parts thereabout in order to permit the removal of the lighter coins which may have been inserted into the chute 60.

It will be seen that I have provided a simple and efficient mechanism which can be usefully operated only by coins of the proper weight, size and denomination; that said mechanism is dependent for its operation on the weight of the coins as well as the proper size and number thereof; and that my improved mechanism is well adapted for the prevention of fraud in the operation of various types of vending mechanism.

While I have shown and described a preferred embodiment of my invention, I do not intend to be understood as limiting myself thereto but intend to claim my invention as broadly as may be permitted by the state of the prior art and the scope of the appended claims.

I claim:

1. The combination with a coin chute pivoted at a point intermediate the ends thereof, open at both ends thereof for the passage of coins and slotted at said ends to expose parts of said coins, of a member of a vending mechanism arranged in the path of the uppermost coin in said chute and adapted to be operated by said member on the swinging of said chute, a lever near the bottom of said chute, a coin supporting member on said lever arranged across the lower slot of said chute, means for swinging said chute for operating

said vending machine member, and a flexible member connected to said vending machine member and to said lever for swinging said lever after said vending machine member has been operated whereby the coins are discharged from said chute.

2. In a vending machine, a movable operating member for the vending mechanism thereof, coin-controlled means for operating said member including a pivoted coin chute adapted to allow the passage of coins completely therethrough, and for operating said member through the intermediary of a coin on the swinging thereof, and means for normally preventing the discharge of coins from said chute until after said member has been operated, comprising a coin supporting lever, means for locking said lever in coin supporting position during the movement of said chute and for unlocking said lever after the movement of said chute has been terminated, and means operatively connecting said operating member to said lever for moving said lever into coin discharging position.

3. In a coin-controlled mechanism, means for receiving a row of coins and for operating a vending mechanism through the intermediary of said coins, and means cooperating with the coin receiving means for normally supporting said row and for discharging the row after the vending mechanism has been operated, said supporting means controlling the operation of said receiving means by automatic adjustment thereof under the weight of said coins.

4. In a coin controlled mechanism, the combination with an operating member of a vending mechanism, of movable coin receiving means, and means controlled by the weight of the coins in said receiving means for positioning the coins in said receiving means in position to engage the operating member on the movement of the coin receiving means together with the coin positioning means.

5. In a coin controlled mechanism, a coin chute, means for swinging said chute for causing the coins therein to operate a vending mechanism when in proper position in said chute, and means controlled by the weight of the coins for positioning said coins for operation of said vending mechanism when the coins are of the proper weight.

6. In a coin controlled mechanism, a coin chute, means for swinging said chute for causing the coins therein to operate a vending mechanism when in proper position in said chute, and means controlled by the weight of the coins for positioning said coins for operation of said vending mechanism when the coins are of the proper weight, said means including a lever, and a swingable member on which said lever is pivoted.

7. In a coin controlled mechanism, means controlled by the weight of the coins inserted into said mechanism for determining the

operative position of the coins comprising a coin-supporting lever, a balancing weight on said lever, and a swingable member to which said lever is pivoted.

8. The method of operating a coin controlled mechanism consisting of supporting a row of coins while exposing the face of the uppermost coin of the row, moving the row so that the face of the uppermost coin operates a member in its path, and determining the position of the row by balancing the weight thereof.

9. In a coin-controlled machine, a pivoted coin chute open at the top and bottom thereof, a pivoted member for normally maintaining the coins in the chute and arranged near the bottom of said chute, means for supporting said member for allowing predetermined depression thereof under the weight of the coins in said chute, a member arranged in the path of the coins in said chute and adapted to be operated by said coins on the pivotal movement of said chute, and means for removing said pivoted member from the bottom of said chute after the member in the path of said coins has been operated and after said chute has been returned to its initial position for discharging the coins from said chute.

10. The combination with a chute normally arranged in upright position and open at both ends thereof, of a member adapted to be operated by the coins in said chute on the swinging of said chute in one direction, means for supporting the coins in said chute in predetermined position for operating said member, manually operable means for swinging said chute to operate said member, means for operatively connecting said member to said coin supporting means for removing said means from the chute and allowing the discharge of the coins from said chute after said chute has been returned to its initial position and before said member has been returned to its initial position.

11. The combination with a member of a vending mechanism, of a swingable coin chute adapted to expose part of the coins therein for the operation of said member on the swinging of said chute, said chute being open at both ends thereof, a swingable lever arranged under said chute, a coin supporting member on said lever on which the coins in said chute are normally supported, means for normally balancing said lever, and means operatively connecting said member to said lever for disturbing the balance of said lever after said member has been operated for allowing the discharge of the coins from said chute by gravity.

12. In a coin-controlled mechanism, the combination with an operating member of a vending machine, of a stationary coin chute, a pivoted coin chute normally aligned with said stationary chute and open at the top and bottom thereof, a pivoted lever near the bot-

tom of said pivoted chute, a coin supporting member on said lever normally arranged across the bottom of said pivoted chute for supporting the row of coins deposited therein, the operating member being arranged in the path of the coins carried by the pivoted chute and being operated by said coins on the swinging of the pivoted chute, and means for operatively connecting said operating member to said lever for swinging said lever to permit the coins in said pivoted chute to be discharged therefrom by gravity.

13. A coin chute pivoted intermediate of the ends thereof and open at both ends for the passage of coins therethrough, means for normally supporting coins in said chute, means for locking the coin supporting means in coin supporting position for movement with said chute as a unit, and means for removing said coin supporting means from coin supporting position after the operation of said chute.

14. In a coin-controlled mechanism, means controlled by the weight of the coins inserted into said mechanism for operating the mechanism, comprising a coin chute and a coin-supporting member movable into predetermined operative position by the weight of the coins in said chute, means for locking the member and the chute together, and means for moving the chute and the member as a unit to operate the mechanism.

15. In a coin-controlled mechanism, a movable coin chute, a weighted member for determining the position of the coins in said chute, and means for locking the member to the chute for movement as a unit.

16. In a coin-controlled mechanism, the combination with an operating member of a vending mechanism, of a coin chute open at the top and bottom thereof, means for swinging the chute for operating said member through the intermediary of the coins therein, and means movable under the weight of said coins for arranging said coins in operative position in said chute only when the coins are of the proper weight, and then movable with the chute as a unit.

17. In a coin-controlled mechanism, a coin chute, a weighted lever for supporting the coins in said chute in operative position therein only when said coins are of the proper weight, and a pivot for supporting said lever for movement in more than one plane.

18. The method of operating a coin-controlled mechanism comprising balancing the weight of a row of coins while maintaining said coins in a substantially vertical row, and swinging the rows of coins against a member in the path of the row to cause one of the coins to operate the member.

19. In a coin-controlled mechanism, a lever pivoted for universal movement and serving to arrange a row of coins in position to operate the mechanism, means for moving the

lever and the row of coins as a unit to operate the mechanism, and to apply stress on one end of the lever in a direction to swing said lever after said mechanism has been operated by the coins and to thereby release the coins.

20. In a coin-controlled mechanism, a lever adapted to sustain a row of coins, means for maintaining the lever in coin sustaining position, and means for applying stress to one end of the lever in a direction to swing the lever while the lever is in coin sustaining position, said means being effective to swing the lever to release the coins only after the maintaining means has released the lever.

MAX WOLNIK.
